UNITED STATES PATENT OFFICE.

HAROLD L. BRIGGS, OF CANASTOTA, NEW YORK.

DESIGN FOR A CRUMB SCRAPER.

Application filed February 18, 1925. Serial No. 12,407. Term of patent 3½ years.

To all whom it may concern:

Be it known that I, HAROLD L. BRIGGS, a citizen of the United States, residing at Canastota, in the county of Madison and State of New York, have invented a new, original, and ornamental Design for Crumb Scrapers, of which the following is a specification, reference being had to the accompanying drawing, forming a part thereof.

The figure is a perspective view of a crumb scraper, showing my new design.

I claim:

The ornamental design for a crumb scraper, as shown.

HAROLD L. BRIGGS.
